United States Patent Office

Des. 232,107
Patented July 16, 1974

232,107

TENNIS RACQUET

Joseph K. Dana, Wilbraham, Mass., assignor to Questor Corporation, Toledo, Ohio

Filed Sept. 5, 1972, Ser. No. 286,432

Term of patent 14 years

Int. Cl. D21—02

U.S. Cl. D34—5 ST

Fig. 1.

Fig. 2.

FIG. 1 is a front view of a tennis racquet showing my new design.

FIG. 2 is a side view.

FIG. 3 is a top view.

FIG. 4 is a bottom view.

The opposite side is substantially similar to that shown.

I claim:

The ornamental design for a tennis racquet, as shown and described.
